SECTIONAL APRON DRIER

Alpheus O. Hurxthal, Philadelphia, Pa., assignor
to Proctor & Schwartz, Incorporated, Philadelphia, Pa., a corporation of Pennsylvania

Application March 25, 1930. Serial No. 438,826

11 Claims. (Cl. 34—12)

This invention relates to apparatus for drying or otherwise treating plastic materials such as paints, pigments, chemicals, etc.

The apparatus in general is similar to that shown and described in my co-pending application, Serial No. 370,662, filed June 13, 1929, which has matured into Patent No. 1,777,972 in which the material to be treated is pressed into the openings of an endless foraminous conveyor apron, which is provided with girts extending beyond the longitudinal side edges of the conveyor in order that the apron may be formed into loops, the loops being suspended from the girts which rest on relatively slow moving horizontally extending supports disposed adjacent the opposite side edges of the apron.

The girts are of necessity spaced relatively far apart to avoid sharp bends in the apron or to prevent undue flexing of the apron in producing the loops, such sharp flexing of the apron, with some kinds of material, having a tendency to loosen the material to such an extent that it falls from the conveyor apron. The relatively wide spacing of the girts on the movable supports requires a relatively large chamber for treating a given amount of material at one time.

The object of the present invention is to minimize the flexing of the apron and to conserve space in the treating chamber.

These objects are attained by forming the apron of a series of separate units or sections, each being of a suitable length, and permanently attaching one end of each section to a carrying pole, or frame, by which the sections of the apron may be each supported in a vertical position and in relatively close relation to each other, the carrying frames extending transversely of the apron and being adapted to be engaged at their opposite ends by propelling lugs carried by endless propelling chains located adjacent the opposite side edges of the apron respectively.

These propelling chains are adapted to run substantially parallel to each other throughout the apparatus for drawing the apron sections through the apparatus. The propelling lugs are positioned on the endless propelling chains at spaced intervals substantially equal to the length of one of the sections of the apron. The carrying or supporting frames extend beyond the side edges of the apron sections and beyond the propelling chains in a manner to be brought to rest on a pair of horizontally movable supports disposed outside the propelling chains, where-

by the frames of the separate sections of the apron will be released from the lugs on the propelling chains, and the sections suspended in vertical relation to each other on the movable supports. The propelling chains after depositing an apron section on and at one end of the movable supports, travel in a plane below the movable supports to the opposite end thereof where the lugs pick up the leading apron section on the movable supports, removing it from the movable supports and propelling it through the apparatus, all as will be fully disclosed hereinafter, reference being had to the accompanying drawings, of which:

Fig. 1 is a diagrammatic longitudinal sectional elevation of an apparatus for treating plastic materials and showing my invention as applied thereto;

Fig. 2 is a diagrammatic transverse sectional elevation taken on the line 2—2, Fig. 1;

Fig. 3 is a diagrammatic sectional plan view taken on the line 3—3, Fig. 1;

Fig. 4 is an enlarged transverse sectional elevation showing an apron section hanging in a vertical position on the movable supports, the section being taken on the line 4—4, Fig. 3;

Fig. 5 is a fragmentary sectional elevation taken on the line 5—5, Fig. 3, and

Fig. 6 is an enlarged detail of the invention.

In the drawings, a suitable casing is diagrammatically illustrated at 1. Rotatably mounted within the casing 1 and extending transversely thereof is a plurality of shafts 2, 3, 5 and 6. Also mounted in each side of the casing and in axial alignment with each other is a pair of short shafts 4, 4. On the opposite ends of each of the through shafts 2, 3, 5 and 6 are secured sprockets 7, 8, 10 and 11 respectively, and on the short shafts 4, 4 at the opposite sides of the casing 1 are sprockets 9, 9 respectively. Passing around the sprockets at each side of the casing is a propelling chain 12.

Between the propelling chains 12, 12 is a material-carrying conveyor apron 15 which comprises a series of ridge supporting frames 16, 16 having projections in the forms of trunnions 17, 17 at their respective opposite ends.

Secured to each of the frames 16 is one end of a flexible foraminous apron section 20, the body portion of which is similar in construction to the foraminous conveyor shown and described in my pending application, Serial No. 305,589, filed September 12, 1928.

On the propelling chains 12, 12 at intervals spaced substantially equal to the length of one

of the apron sections 20, is a pair of propelling lugs 18, 18 respectively, which are adapted to engage respectively the trunnions 17, 17 on the frames 16, so that the chains 12, 12 and the 5 apron sections 20, 20 carried therebetween will move through a portion of the apparatus the same as a continuous flat conveyer, the free back end 21 of each apron section 20 occupying a position immediately adjacent the forward 10 edge 22 of the frame 16 of the next successive apron section 20.

The empty apron sections 20, of the conveyer 15, are adapted to be carried successively around and over the top of a roller 26, which is mounted 15 on the shaft 2, while the propeller chains 12, 12 pass around the sprockets 7, 7 on the said shaft.

The apron sections 20 are then passed in a 20 substantially horizontal plane through a suitable pasting mechanism 25, where the material x , in a plastic state, is pressed into the openings 24 (see Fig. 4) of each of the successively presented apron sections 20.

After the material to be treated has been 25 pressed into the conveyer sections 20 the said loaded sections pass under and partly around a roller 27, which is mounted on the shaft 3 between the sprockets 8, 8 thereon, while the propeller chains 12, 12 pass around the sprockets 8, 8, on the said shaft.

Each apron section 20, after passing under 30 the roller 27, assumes a substantially vertical plane and is supported therein by its girt 16, which in turn is supported and carried by the propeller chains 12, 12. The trunnions 17, 17 of the apron section lie on the lugs 18 between the chains 12, 12 and vertically disposed guides 35 located at opposite sides of and in one end of the casing 1.

40 The frames 16 are successively raised in this vertical plane until the rear end 21 of the conveyer section 20 carried by each girt has passed completely from under the roller 27, whereupon the girt 16 is carried over the top of the sprocket wheels 9, 9 on the short shafts 4, 4.

As each frame 16 passes around the upper 45 side of the sprockets 9, 9 the loaded apron section 20 supported thereby is maintained in a vertical plane and while in this position the apron section 20 is transferred bodily in a direction substantially longitudinal of the casing 1, from one side of the axis of rotation of the sprockets 9, 9 to a position at the opposite side of said axis, the short shafts 4, 4 disposed respectively at opposite sides of the casing 1 being spaced a sufficient distance apart to permit the apron section 20 to pass therebetween.

After the frame 16 passes over the top of the sprockets 9, 9 the outer ends of the trunnions 50 17, 17 of the frame, which extends beyond the propeller chains 12, 12, engage inclined guides 29, 29 disposed respectively at the opposite sides of the casing 1, and as the chains 12, 12 move forward over the sprockets 9, 9 the frame 16 is permitted to slide easily down the inclined guides 55 29, 29, until the outer ends of the trunnions 17, 17 of the frame come to rest on relatively slow moving supports 30, 30 disposed respectively at opposite sides of the casing 1. In this manner 60 the frame trunnions 17, 17 are released from the lugs 18, 18 of the propeller chains 12, 12.

The slowly moving supports 30, 30 in the 65 present instance, comprise sprocket chains which pass around sprocket wheels 31, 31 mounted on the transversely extending short shafts 4, 4

located at opposite sides of the casing 1, the chains 30, 30 passing also around sprockets 33, 33 mounted on the transversely extending through shaft 5 disposed at the opposite end of the casing 1.

The supporting chains 30, 30 are adapted to be driven by any suitable means and at any pre-determined rate of speed relative to the rate of speed of travel of the propelling chains 12, 12, the relation of the speed of travel of the propelling chains and that of the supporting chains 30, 30 determining the relative spacing of the apron sections 20, 20 on the moving supports 30, 30.

After the trunnions 17, 17 of a frame 16 90 have been released from the propeller lugs 18, 18 and deposited on the movable supports 30, 30 the chains 12, 12 pass downwardly and under sprockets 34, 34, thence parallel to the supports 30, 30 and around sprockets 35, 35 as clearly 95 shown in Fig. 1.

As the leading section 20 approaches the delivery end of the casing 1 the propelling lugs 18, 18 on the propeller chains 12, 12, as the chains pass upwardly from the sprockets 35 to 100 and around the sprockets 10, 10 on the shaft 5, engage the trunnions 17, 17 of the leading frame 16, whereupon the said leading frame is raised from the said movable supports 30, 30 and carried upwardly and around the sprockets 10, 105 10, the apron section 20 supported by the said frame passing around and over a roller 40 which is mounted on the shaft 5 between the sprockets 10, 10 thereon.

The support chains 30, as shown in Figs. 4 110 and 5 are provided with rollers 36 which ride on suitable supporting rails 37, carried by the framework of the casing 1. Obviously, the movable supports 30 may be in the form of longitudinally extending feed screws into the grooves 115 of which the ends of the trunnion 17 may be deposited and carried longitudinally of the casing 1, if desired, or any other suitable form of movable support may be provided which will carry the sections 20 of the conveyer 15 in spaced 120 relation to each other through the casing 1.

During the passage of the conveyer sections 20 through the casing 1 the material carried by the said sections is subjected to a drying or other suitable treatment or processing and 125 is thereby made ready to be removed from the conveyer 15.

After passing over the sprockets 10, 10 the frame 16 is fed downwardly in the casing, between a pair of substantially vertically disposed 130 guides 41 and 42, there being a pair of such guides adjacent each of the opposite sides of the casing 1, these guides being so positioned with respect to the conveyer 15 that they engage the various conveyer sections 20 inwardly of and 135 immediately adjacent the longitudinal side edges thereof, as shown in Fig. 2, so that as each conveyer section 20 moves downwardly in the casing 1, with the frame 16 thereof leading the particular section 20 to which the frame is 140 attached, the said conveyer section will be supported in a substantially vertical plane, preventing the section from collapsing and falling into a heap at the bottom of the casing.

While in position between the guides 41 and 145 42 the conveyer section 20 is subjected to a tapping or heating operation effected by a suitable beater 45 which is adapted to be intermittently moved away from the conveyer section and then permitted to strike the said conveyer 150

section a sharp blow, in order to beat the material out of the openings of the conveyer section, the material falling into a suitable hopper 46 at the bottom of the casing, the hopper being 5 provided with a feed screw 47 which is adapted to remove the material from the casing 1.

Adjacent the lower end of the casing the propeller chains 12, 12 pass around the sprockets 11, 11 on the shaft 6 thereby carrying the frame 10 16 around said sprockets and around a roller 48 mounted on the shaft 6 intermediate the sprockets 11, 11 thereon, the body of the apron section 20 attached to the frame 16 passing around the roller 48 and onto a horizontally 15 disposed platform or partition 50, located in the casing 1 near the bottom thereof, by the lugs 18 on the propeller chains 12 engaging the trunnions 17, 17 of the frame 16.

As the chains 12, 12 move horizontally over 20 the platform 50 the conveyer sections 20 are drawn by their frames 16 along the partition or floor 50 and return to the feed end of the apparatus, at which the shaft 2 and roller 7 are located. The platform 50 is curved upwardly and around the roller 26 and sprockets 25 7, 7, as illustrated at 51 to maintain contact between the lugs 18 and the frame trunnions 17 while the conveyer sections are being carried around the roller 26.

30 From the above description, it will be apparent that from the time the material is placed in the sections 20 of the conveyer 15 until the processed material is finally removed from such sections at the delivery end of the apparatus the loaded apron sections are subjected to but one flexing operation and this is effected over a roller having such a relatively large diameter that very little relative flexing between the components of the conveyer section occurs, 35 consequently the tendency of the material to fall from the conveyer sections before the processing has been completed is reduced to a minimum.

It will also be obvious from the above 40 description that considerable space is saved in the drying chamber by my being able to arrange the sections of the conveyer relatively close to each other.

I claim:

50 1. In an apparatus for treating plastic material, a foraminous conveyer comprising a plurality of separate sections, propelling means separate from the sections for advancing the sections in end to end relation through a portion of the apparatus, and a second propelling means separate from the first said propelling means and separate from the sections for advancing the sections through another portion of the apparatus in substantially parallel side by side relation to each other.

2. In an apparatus for treating plastic material, a foraminous conveyer comprising a plurality of separate sections, propelling means separate from the sections for advancing the sections in end to end relation through a portion of the apparatus, a second propelling means separate from the first said propelling means and separate from the sections for advancing the sections through another portion of the apparatus in substantially parallel side by side relation to each other, and means for transferring said sections from one to the other of said propelling means.

3. In an apparatus for treating plastic material, a foraminous conveyer comprising a plu-

rality of separate sections, each having a laterally extending projection on each of its oppositely disposed side edges at one end of the section, propelling means separate from the sections and adapted to engage the projections thereon for advancing the sections in end to end relation through a portion of the apparatus, and a second propelling means separate from the first said propelling means and separate from the sections and adapted to engage the projections thereon for advancing the sections through another portion of the apparatus in substantially parallel side by side relation to each other. 80

4. In an apparatus for treating plastic material, a foraminous conveyer comprising a plurality of separate sections, each having a laterally extending projection on each of its oppositely disposed side edges at one end of the section, propelling means separate from the sections and adapted to engage the projections thereon for advancing the sections in end to end relation through a portion of the apparatus, a second propelling means separate from the first said propelling means and separate from the sections and adapted to engage the projections thereon for advancing the sections through another portion of the apparatus in substantially parallel side by side relation to each other, and means 90 adapted to engage the said projections for transferring said sections from one to the other of 95 said propelling means.

5. In an apparatus for treating plastic material, a foraminous conveyer comprising a plurality of separate sections, each having a laterally extending projection on each of its oppositely disposed side edges at one end of the section, propelling means separate from the sections and adapted to engage the projections thereon for advancing the sections in end to end relation and in a substantially horizontal plane 110 through a portion of the apparatus, and a second propelling means separate from the first said propelling means and separate from the sections and adapted to engage the projections thereon for advancing the sections through another portion of the apparatus in substantially parallel planes in side by side relation to each other. 115

6. In an apparatus for treating plastic material, a foraminous conveyer comprising a plurality of separate sections, each having a laterally extending projection on each of its oppositely disposed side edges at one end of the section, propelling means separate from the sections and adapted to engage the projections thereon for advancing the sections in end to end relation and in a substantially horizontal plane through a portion of the apparatus, a second propelling means separate from the first said propelling means and separate from the sections and adapted to engage the projections thereon for advancing the sections through another portion of the apparatus in vertical substantially parallel planes in side by side relation to each other. 125

7. In an apparatus for treating plastic material, a foraminous conveyer comprising a plurality of separate sections, each having a laterally extending projection on each of its oppositely disposed side edges at one end of the section, propelling means separate from the sections and 130

adapted to engage the projections thereon for advancing the sections in end to end relation and in a substantially horizontal plane through a portion of the apparatus, a second propelling means separate from the first said propelling means and separate from the sections and adapted to engage the projections thereon for advancing the sections through another portion of the apparatus in vertical substantially parallel planes in side by side relation to each other, means at one end of the apparatus for guiding said sections from the said horizontal plane into the said vertical plane, means for transferring the sections from one to the other of said propelling means while the sections are in a vertical plane, and means at the opposite end of the apparatus for transferring the said sections from the side by side relation on the second said propelling means to the said end to end relation on the first said propelling means.

8. In an apparatus for treating plastic material, a foraminous conveyer comprising a plurality of separate sections, each having a laterally extending projection on each of its oppositely disposed side edges at one end of the section, propelling means separate from the sections and adapted to engage the projections thereon for advancing the sections in end to end relation and in a substantially horizontal plane through a portion of the apparatus, a second propelling means separate from the first said propelling means and separate from the sections and adapted to engage the projections thereon for advancing the sections through another portion of the apparatus in vertical substantially parallel planes in side by side relation to each other, means at one end of the apparatus for guiding said sections from the said horizontal plane into the said vertical plane, means for transferring the sections from one to the other of said propelling means while the sections are in a vertical plane, means at the opposite end of the apparatus for transferring the said sections from the side by side relation on the second said propelling means to the said end to end relation on the first said propelling means, and means for guiding said sections into the said horizontal plane.

9. In an apparatus for treating plastic material, a foraminous conveyer comprising a plurality of separate sections each having a laterally extending projection on each of its oppositely disposed sides at one end of the section, propelling means for said sections comprising a pair of endless chains disposed respectively ad-

jacent the oppositely disposed longitudinal side edges of the conveyer, lugs on the said propelling chains adapted to engage the said projections on the separate conveyer sections, and a second propelling means separate from the first said propelling means and movable in a path intersecting the path of travel of the first said propelling chains for engaging the projections on the conveyer sections.

10. In an apparatus for treating plastic material, a foraminous conveyer comprising a plurality of separate sections each having a laterally extending projection on each of its oppositely disposed sides at one end of the section, propelling means for said sections comprising a pair of endless chains disposed respectively adjacent the oppositely disposed longitudinal side edges of the conveyer, lugs on the said propelling chains adapted to engage the said projections on the separate conveyer sections, a second propelling means separate from the first said propelling means and movable in a path intersecting the path of travel of the first said propelling chains for engaging the projections on the conveyer sections, and means for transferring the separate conveyer sections from the first said propelling means to the second said propelling means.

11. In an apparatus for treating plastic material, a foraminous conveyer comprising a plurality of separate sections each having a laterally extending projection on each of its oppositely disposed sides at one end of the section, propelling means for said sections comprising a pair of endless chains disposed respectively adjacent the oppositely disposed longitudinal side edges of the conveyer, lugs on the said propelling chains adapted to engage the said projections on the separate conveyer sections, a second propelling means separate from the first said propelling means and movable in a path intersecting the path of travel of the first said propelling chains for engaging the projections on the conveyer sections, means for transferring the separate conveyer sections from the first said propelling means to the second said propelling means, means for supporting the independent conveyer sections in end to end relation with respect to each other while under control of the first said propelling means, and means for supporting the said sections in substantially parallel side by side relation to each other while under the control of the second said propelling means.
